SAMUEL BUREN, OF NEW YORK, N. Y.

METHOD OF OPERATING THERMIONIC-DISCHARGE DEVICES.

Application filed April 3, 1923. Serial No. 629,708.

This invention relates to a means for maintaining thermionic discharge currents at constant values. Its principal object is to provide a simple, highly efficient means 5 for stabilizing thermionic discharges within much closer limits than is now possible by any present employed device.

In the various devices operative by discharge of thermionic currents, and especially those in which the cathodes are brought 10 to high temperature for emission, it is important to maintain the thermionic currents at a high degree of constancy, and, in some applications, to prevent overloading due to 15 variations in the discharge conditions. In these devices two factors are normally variable, namely, the emission element temperature and the conditions in the path of discharge, such as the degree of vacuum or 20 pressure. As the potential for driving the thermionic discharge through the space is usually above the saturation value, any normal variations thereof are negligible in effect.

25 To maintain constant conditions of operation, it is therefore necessary to compensate for variations in only those two factors. Variation in space conditions in the highly evacuated type of apparatus is usually 30 due to the liberation of gas from the parts within the container, which become heated by the kinetic energy of impact of the cathode discharge. In that type, such for instance, as the X ray tube operating by a 35 heated cathode filament as the source of electron emission, slight gas liberation causes reduction in the discharge current and in the resultant work or effect of the emission, that is, the X ray radiation. To 40 obtain the best results, these conditions must be maintained at a constant value. In those thermionic discharge devices in which the pressure is not so low, excessive positive ionization overheats the cathode with a 45 rapidly increasing effect in the tube, soon destroying the filament by the bombardment of the positive ions.

Various means have been employed to 50 stabilize the electron stream upon the anode, but they have been only partially successful because of lack of close and continuous adjustment, slowness of action and inapplicability for use with high potentials. My invention is not so limited. It consists broadly 55 of an arrangement and connection of electrical apparatus by which an element

having a high coefficient of resistance, in series with the emission element of the thermionic device to be controlled, and the resistance of which is directly controlled by 60 the thermionic discharge current to be controlled or stabilized, is employed, in turn, by its variable resistance, to control the cathode supply current.

The resistance element which is preferably 65 an iron wire, formed so as to present a large radiation area, as in a coil, constituting the plate element in a thermionic discharge, or regulating device, is heated by the current supplying the heat energy for 70 the cathode of the device to be controlled, also by impact of the electron stream from its own cooperating electrode, the potential therefor being obtained from a high resistance element in series with the cathode of 75 the device to be controlled.

Due to its normally high temperature and large radiation area, the plate element radiates heat at a high rate, and its response in electrical resistance, to temperature changes, 80 is very quick.

As the kinetic energy of impact of the thermionic discharge in the regulating device heats its iron anode and increases the resistance thereof, any variation in the thermionic discharge in the controlled device causes a variation in the temperature of the anode of the regulating device, and by the effect of that impact, its resistance. This causes a variation in the current flowing 85 therethrough and through the cathode of the controlled device, and therefore, in the thermionic discharge therefrom, and in turn, a variation in the thermionic discharge 90 in the regulating device, with resultant effect upon the anode, and so on. The operation of the regulating device consequently, compensates for such variations, and maintains the thermionic discharge in the controlled device at constant value. 100

It was found that when this arrangement was applied to X ray tube control, due to the very rapid thermal radiation from the anode of the regulating device, the X ray tube current was maintained with no 105 perceptible fluctuation, even when wide variations occurred in the supply current.

The principle of the invention can best be further explained in connection with a certain illustrative embodiment of the invention 110 in connection with an X ray tube, as one type of thermionic discharge device, as

shown in the accompanying drawing; but it is to be understood that the invention is also applicable to other devices operating by thermionic discharges, such as rectifiers, 5 radio generators, etc.

The drawing illustrates the arrangement and connection of an X ray tube operating by thermionic discharge, with the electrical apparatus by means of which its discharge 10 is stabilized.

Referring more particularly to the drawing, 1 represents the X ray tube and 2, 2^a and 3 respectively, the emission element, the focussing element and the anode. At 4 is the regulating, or thermionic discharge device, with cathode 5 and anode 6. At 7 is a 15 variable resistance, and at 8, resistance in series with cathode 2, to give the resistance drop of potential for operating the regulating device 4. At 9 and 10 respectively are the secondary elements of the heating circuits for cathodes 5 and 2, 11 being the primary, the current being supplied therefor at terminals 12, 13 being the terminals for 20 the high potential direct current for the necessary potential for X ray radiation.

In operation, when a potential is applied at terminals 12, cathode 2, in tube 1, and cathode 5, in regulating tube 4, are heated 30 to electron emission temperature. Anode 6, of the regulating tube is heated by the heating current in series circuit with cathode 2, the amount through it controlled by its resistance. A high voltage being applied to 35 terminals 13, a thermionic current discharges between the electrodes in tube 1, and, due to the potential drop across resistance 8, a thermionic current discharges between cathode 5 and anode 6, of the regulating tube. Anode 40 6, is also heated by the kinetic energy of the thermionic discharge impact upon it carried by the difference of potential across the resistance 8. Current supplied to cathode 2, of tube 1, is reduced accordingly as the resistance of anode 6, increases. To establish 45 the desired normal operating conditions resistance 7, is varied until that current is discharged through tube 1, and resistance element 7, is set at that point. If then the 50 thermionic current in tube 1, is then reduced in operation, by reason of the liberation of gas, as described, the discharge from cathode 5, upon anode 6, is reduced, and, due to its high resistance, coefficient, its temperature 55 and resistance are decreased, thereby permitting an increase in the current heating cathode 2 until the normal current again discharges through it.

For certain applications resistance element, 8, can be omitted from the circuit, when the normal resistance drop of potential across the regulating tube itself is sufficient.

What I claim is:—

65 1. The combination with a thermionic dis-

charge device, of another thermionic discharge device having an anode composed of a material of a high coefficient of resistance connected in series with the cathode of said first named device, and means for controlling 70 the discharge from said cathode by the thermionic discharge in said second named device, in response to variations in the discharge from said cathode.

2. The combination with a thermionic discharge device, of another thermionic discharge device having an anode composed substantially of iron connected in series with the cathode of said first named device, and means for controlling the discharge from 80 said cathode by the thermionic discharge in said second named device, in response to variations in the discharge from said cathode.

3. The combination with a thermionic discharge device, of another thermionic discharge device having an anode composed of a material of high coefficient of resistance connected in series with the cathode of said first named device, and means for controlling 85 the resistance of said anode by variations of the thermionic discharge from its cooperating electrode upon the anode in said second named device, in response to variations in the thermionic discharge from said cathode.

4. The combination with an X ray tube, of a thermionic discharge device, with means for controlling the thermionic discharge of said X ray tube by the impact of the thermionic discharge in said thermionic discharge device, in response to variations in the thermionic discharge in said X ray tube.

5. The combination of an X ray tube with a thermionic discharge device with means for controlling the current flowing through 105 the cathode of said tube, by variations in the resistance of the anode element of said device in response to the impact of the thermionic discharge from its cooperating electrode in response to variations in the thermionic discharge in said X ray tube.

6. The combination of an X ray tube with a thermionic discharge device having its anode element connected in series with the cathode of said tube, and means for controlling the thermionic discharge from said cathode by the resistance of said anode controlled by the thermionic discharge from said cathode.

7. In combination, a thermionic device, 120 with another thermionic device having an anode connected in series with the cathode element of said first named device, said anode having a coefficient of resistance higher than the coefficient of resistance of 125 said cathode, and the discharge from said cathode being variable by the thermionic discharge in said second named device, in response to variations in the discharge from said cathode.

8. An arrangement for stabilizing the discharge in a thermionic device which comprises, in electrical connection a thermionic device, a second thermionic device, said second mentioned device having its anode connected in series with the cathode of said first mentioned device, and having a higher coefficient of resistance than the coefficient of resistance of said cathode, said anode and said cathode being connected in series with a source of heating energy, a source of heating energy in the circuit of said second mentioned device, means for varying the potential between the cooperating electrodes of

said second mentioned device, a source of potential for said first mentioned device, a resistance connected in series in the circuit between said source of potential and the cathode of said first named device, and an electrical connection between both of said cathodes, so arranged that a variation in the plate potential of said first mentioned device produces a variation in the plate potential of said second mentioned device. 15
